TYPOGRAPHICAL SLUG CASTING MACHINE

Richard Henry Scott, Enfield, and William Fairall Gorse and Arthur Staniland Hayward, Altringham, England, assignors to Linotype and Machinery Limited, London, England, a British company

Application September 11, 1940, Serial No. 356,290
In Great Britain October 20, 1939

19 Claims. (Cl. 199—48)

This invention relates to typographical slug casting machines such as are commercially known under the registered trade-mark "Linotype."

In such machines the lines of matrices from which the slugs are cast are brought against molds which are located against slots in a mold disc. At the rear side of this disc a pot is disposed which contains type metal in a molten condition and this metal is forced into the mold at the appropriate time to form the slug. Owing to the fact that the lines of type and consequently the slugs on which they are formed are generally required to be of a more or less defined length it has not, as a rule, been found possible to provide more than two or four molds on the mold disc without unduly increasing the size of the disc and consequently of other parts of the machine. One of the main objects of the present invention is to overcome this difficulty and to provide a machine wherein an increased number of molds may be employed. With this end in view the invention provides a rotatable mold carrier for a typographical slug casting machine of the kind referred to which is adapted to accommodate the molds at or upon its periphery. Preferably the periphery of the carrier is provided with a plurality of mold seatings thereon and consequently the carrier, instead of being circular as ordinarily, is in the form of a substantially polygonal plate. For example, when seatings for six molds are provided, the carrier may be substantially hexagonal in configuration. The mold seatings are preferably separated by projecting members to which the molds are secured.

A further feature of the invention resides in the manner in which the mold carrier is driven and from this aspect the same comprises a machine of the type specified wherein the mold carrier is driven from or through a shaft upon which it is arranged. Advantageously, the whole or a portion of the drive is enclosed. Hitherto, it has been customary to provide the mold carrier with a geared circumference and to drive the same by means of a pinion in engagement therewith. The present invention eliminates this pinion thereby economising space in this part of the machine.

The mold may be composed, as usual, of a body having a matrix aligning mold cap and two liners manufactured as separate parts and the mold body may be secured to the carrier in a substantially permanent manner, for example by means of screws. It is an important feature of the in-

vention, however, that the use of fitted gibs or keys, by means of which it has been customary to fit the cap to the body of the mold, is dispensed with, and the height of the mold aperture may be determined by adjustment of the cap in relation to the body by means of adjustable screws or the like.

In order that the invention may be more clearly understood a preferred embodiment thereof will now be described in detail with reference to the accompanying drawings in which:

Figure 1 is a front elevation of one form of a rotatable mold carrier for a typographical slug casting machine according to the invention;

Figure 2 is a longitudinal section through Figure 1;

Figure 3 is a more detailed view of a mold forming part of the invention;

Figure 3A is a section on line A—A of Fig. 3 looking in the direction of the arrows;

Figure 4 is a plan view of the mold slide shown in Figures 1 and 2.

Referring to the drawings, the constructional form of mold carrier therein represented consists of a flat substantially hexagonal plate 1 having six mold seatings 2 formed on its periphery, which seatings are divided from one another by means of projecting members 3 shaped to engage with and accommodate the mold. The said projecting members 3 are provided with a ledge 4 adapted to accommodate a liner 5 against which the body of the mold 6 rests and a gap 7 is provided to allow the mold cap 9 to be clamped downwardly by means of screw bolts or the like 8, or a plurality thereof, which enter holes in the projecting members 3 whereby the mold cap 9 is secured upon the body of the mold and to the carrier. The said screws are adjustable so that the height of the mold aperture may be varied as desired. If desired, the adjustable mold cap 9 may be provided at its opposite ends with clamping screws 8^a which, when tightened up against the projecting members 3, will aid in maintaining the cap in its adjusted position. Any keys or gibs which might in previous practice be fitted to the mold form in the present invention a part of the mold carrier. The mold may be provided with liners on either side thereof in the manner customary in the art.

Conveniently the drive is taken from the main drive of the machine through shafts connected by spiral gearing. The mold carrier 1 is mounted on a shaft 10 on which is also mounted a spiral gear 11 which is in engagement with a pinion 12. The shaft 10 is carried in bearings 13 and 14

which are mounted in the mold slide. The spiral gear 11 is keyed to the shaft 10 by means of a key 15 and is held laterally by means of a split ring 16 and bearing 14 which is a combined radial thrust bearing. The ring 16 is fixed by screws to the gear 11 and let into a groove in the shaft 10. Bearing 13 is a ball bearing. The said pinion 12 is mounted upon an intermediate shaft 17 which runs at right angles to the mold carrier shaft, and a second spiral gear 18 is mounted at the opposite end of the intermediate shaft 17 to that which carries the pinion 12. The intermediate shaft 17 is carried on radial ball thrust bearings 19 and 20 which are mounted in the mold slide 21 and held laterally by end plates 22 and 23. A driving spindle 24 which may be disposed in parallel relation to the mold carrier shaft 10 engages the spiral gearing 18 on the intermediate shaft 17 by means of a pinion 25 suitably secured to the said spindle 24. The spindle 24 has a sleeve 26 pinned thereon and the sleeve 26 is driven from the main driving shaft 27 of the machine through splined keys 28.

Advantageously, means are provided for rotating the mold carrier by hand and such means preferably consist in a hand turning sleeve 29 connected to the driving spindle 24 by means of a tongue piece 30 fixed to the sleeve 29 by screws 31. The tongue piece 30 engages in a slot 32 in the said spindle 24 and is secured therein by means of a spring 33. The pinion 25 which carries the drive from the driving spindle 24 to the intermediate shaft 17 is provided with a long boss 34 and is secured to the hand turning sleeve by means of a key 35 which engages the said boss, and also a groove in the hand turning sleeve 29. When it is desired to rotate the mold carrier by hand the hand turning sleeve 29 is freed from the driving spindle by pulling the sleeve 29 outwards so as to disconnect the tongue 30 from the slot 32 in the said spindle 24 when the pinion 25 may be rotated by manual operation of the said sleeve whereby the pinion is turned through the key engaging the sleeve thereon.

Parts of the drive may be enclosed and in particular it is desirable to enclose the spiral gear drives and these are conveniently enclosed within housings which form a part of the mold slide. This construction is shown in the drawings wherein the gears 12 and 18 are enclosed in housings 36 and 37 respectively.

Thrust guides 38, 39 are provided to prevent the mold carrier 1 from springing away when the mold is passing over the back knife 40 and such guides may be of the kind at present usually employed.

Having described our invention, we declare that what we claim and desire to secure by Letters Patent is:

1. In or for a typographical slug casting machine, a rotatable mold carrier having a plurality of mold seatings formed on its periphery, in combination with driving means for imparting a complete rotation to the mold carrier at each casting cycle of the machine, said driving means operating on the mold carrier within its peripheral limits so as to leave said carrier entirely free at its periphery to accommodate the molds.

2. In or for a typographical slug casting machine, a flat rotatable mold carrier of substantially polygonal form and having each of its edges adapted to accommodate a mold thereon, in combination with driving means for imparting a complete rotation to the mold carrier at each casting cycle of the machine, said driving

means operating on the mold carrier within its peripheral limits so as to leave said carrier entirely free at its periphery to accommodate the molds.

5. In or for a typographical slug casting machine, a rotatable mold carrier having a plurality of mold seatings formed on its periphery, and projections between adjoining mold seatings adapted for the securing of the molds thereto, in combination with driving means for imparting a complete rotation to the mold carrier at each casting cycle of the machine, said driving means operating on the mold carrier within its peripheral limits so as to leave said carrier entirely free at its periphery to accommodate the molds.

10. In or for a typographical slug casting machine, a mold assembly comprising a rotatable mold carrier having a plurality of mold seatings formed on its periphery and a mold adjustably secured in each of said seatings.

15. In or for a typographical slug casting machine, a mold assembly comprising a mold carrier having a plurality of mold seatings on its periphery, projections between adjoining mold seatings and a mold in each of said seatings adjustably secured to said projections.

20. In or for a typographical slug casting machine, a mold assembly comprising a rotatable mold carrier having a series of mold seatings formed on its periphery and projections between adjoining mold seatings, said projections being provided with ledges, a mold cap associated with each seating adjustably secured to said ledges and a mold body disposed in each of said seatings so that the height of the respective mold aperture may be varied.

25. In a typographical slug casting machine, the combination of a mold carrier, a rotatable shaft upon which said mold carrier is mounted, and means independent of the mold carrier for driving said shaft, said means acting to impart a complete rotation to the mold carrier at each casting cycle of the machine.

30. In a typographical slug casting machine, the combination of a mold carrier, a rotatable shaft upon which said mold carrier is mounted, a main driving shaft and spiral gearing connecting said rotatable shaft with said main driving shaft.

35. In a typographical slug casting machine, the combination of a mold carrier, a rotatable shaft upon which said mold carrier is mounted, a main driving shaft and enclosed spiral gearing connecting said rotatable shaft with said main driving shaft.

40. In a typographical slug casting machine, the combination of a rotatable mold carrier, a mold slide, a rotatable shaft upon which said mold carrier is mounted, a main driving shaft, an intermediate shaft mounted in said mold slide, gearing at both ends of said intermediate shaft through which said rotatable shaft is driven and housings in said mold slide enclosing said gearing.

45. In a typographical slug casting machine, the combination of a rotatable mold carrier, a mold slide, a rotatable shaft upon which said mold carrier is mounted, a main driving shaft, an intermediate shaft mounted in said mold slide, a spindle driven by said main driving shaft, gearing at one end of said intermediate shaft connected to said spindle, a gearing at the other end of said intermediate shaft connected to said rotatable shaft, and housings in said mold slide enclosing said gearings.

12. In a typographical slug casting machine, the combination of a rotatable mold carrier having a plurality of mold seatings on the periphery thereof, a rotatable shaft upon which said mold carrier is mounted, means independent of the mold carrier for driving said shaft, said means acting to impart a complete rotation to the mold carrier at each casting cycle of the machine, and means independent of the driving means for rotating said shaft to adjust the mold carrier with reference to said driving means in changing from one mold to another.
13. In a typographical slug casting machine the combination with a rotatable mold carrier having a plurality of mold seatings on the periphery thereof and projections between adjoining mold seatings, adapted for the securing of the molds thereto, of a rotatable shaft upon which said mold carrier is mounted, driving means independent of the mold carrier for said rotatable shaft, said means acting to impart a complete rotation to the mold carrier at each casting cycle of the machine, and means independent of the driving means for rotating said shaft to adjust the mold carrier with reference to said driving means in changing from one mold to another.
14. In a typographical slug casting machine the combination of a rotatable mold carrier having a plurality of mold seatings on the periphery thereof, with molds secured in said seatings, a rotatable shaft on which said mold carrier is mounted, a main driving shaft and driving connections between said main driving shaft and said rotatable shaft, said driving connections including an intermediate shaft and gearing.
15. In a typographical slug casting machine the combination of a rotatable mold carrier having a plurality of mold seatings on the periphery thereof and projections between said mold seatings, with a mold slide, a rotatable shaft, upon which said mold carrier is mounted, a main driving shaft, an intermediate shaft mounted in said mold slide, gearing at both ends of said intermediate shaft connecting said intermediate shaft with said main driving shaft and with said rotatable shaft, and housings in said mold slide enclosing said gearing.
16. In a typographical slug casting machine, the combination with a rotatable mold carrier of mechanical driving means therefor including a rotatable shaft upon which said mold carrier is mounted, and means operable by hand for turning said mold carrier independently of said mechanical driving means.
17. In a typographical slug casting machine, the combination with a rotatable mold carrier having a plurality of mold seatings on the periphery thereof, of mechanical driving means for said mold carrier including a rotatable shaft, upon which said mold carrier is mounted and means operable by hand for turning said mold carrier independently of the mechanical driving means.
18. In a typographical slug casting machine, the combination with a rotatable mold carrier having a plurality of mold seatings on the periphery thereof and mechanical driving means for said mold carrier including a rotatable shaft upon which said mold carrier is mounted, of a hand operated member releasably secured to a member of said driving means for manually turning said mold carrier.
19. In a typographical slug casting machine, the combination of a rotatable mold carrier having a plurality of mold seatings formed on the periphery thereof, a mold slide, a rotatable shaft upon which said mold carrier is mounted, a main driving shaft, a spindle driven by said main driving shaft, an intermediate shaft mounted in said mold slide, spiral gearing at one end of said intermediate shaft connecting said rotatable shaft with said intermediate shaft, spiral gearing at the other end of said intermediate shaft connecting said intermediate shaft with said spindle, a hand turning sleeve releasably secured to said spindle and a key on said spindle engaging a groove in an extension of said spiral gearing so that on release of said turning sleeve from said spindle, said sleeve is in engagement with said spiral gearing to enable said mold disc to be manually rotated.
